MATTHEW M. BEAM, OF OLD FORGE, PENNSYLVANIA.

SAFETY DEVICE FOR ELEVATORS.

1,134,582.

Specification of Letters Patent.

Patented Apr. 6, 1915.

Application filed April 6, 1914. Serial No. 829,962.

To all whom it may concern:

Be it known that I, MATTHEW M. BEAM, a citizen of the United States, residing at Old Forge, in the county of Lackawanna and State of Pennsylvania, have invented a new and useful Safety Device for Elevators, of which the following is a specification.

The invention relates to improvements in safety devices for elevators.

10 The object of the present invention is to improve the construction of safety devices for elevators and to provide an auxiliary operating device in the nature of an attachment, adapted to be applied to elevators 15 equipped with safety devices of the ordinary construction, and capable of rendering absolutely certain the operation of the dogs in gripping the guides to arrest the descent of an elevator car should the automatic operating means with which such devices are 20 ordinarily equipped become inoperative through any breakage or defect of springs, loss of resiliency of rubber, or the filling in with ice of the space provided for the expansion of the springs, and the like.

A further object of the invention is to provide an auxiliary operating device of this character adapted, when the cable of the car parts at the clamp or socket, of positively actuating the dogs, and equipped 30 with flexible means for operating the dogs, so that one dog will not interfere with the action of another, and by engaging the guide in advance of the other dogs, interfere 35 with the operation of the latter, which is liable to occur with safety devices of the ordinary construction when the guides or gages are not in plumb and one dog hangs closer to a guide than another.

40 With these and other objects in view the invention consists in the construction and novel combination of parts hereinafter fully described, illustrated in the accompanying drawing, and pointed out in the claims hereinafter appended, it being understood that various changes in the form, proportion, size, and minor details of construction, within 45 the scope of the claims, may be resorted to without departing from the spirit or sacrificing any of the advantages of the invention.

In the drawing:—Figure 1 is an elevation of a portion of an elevator car or cage hav-

ing a safety device equipped with auxiliary operating means constructed in accordance 55 with this invention. Fig. 2 is a horizontal sectional view on the line 2—2 of Fig. 1. Fig. 3 is a vertical sectional view on the line 3—3 of Fig. 1.

Like numerals of reference designate corresponding parts in all the figures of the drawings.

In the accompanying drawings, in which is illustrated the preferred embodiment of the invention, 1 designates an elevator car 65 or cage equipped with a safety device comprising spaced pivotally mounted dogs 2 arranged in pairs and forming clutches to grip the guides (not shown) of an elevator shaft in the usual manner. The dogs are 70 connected by links 3 with the outer ends of horizontal levers 4, located below and at opposite sides of the top beam 5 of the cage or car 1 and connected at their inner ends with an automatic operating device 6 by 75 short inner links 7. The levers 4, which are disposed transversely of the elevator car or cage, are fulcrumed intermediate of their ends on suitable pivots 8, and the links 3 are provided at their upper ends with vertical slots 9 for the reception of the pivots 10, which connect the links and the outer ends of the levers 4.

The operating device 6, which is connected to the lower end of a central vertical 85 holding rod 11, may be of any desired construction, and it is maintained under tension by the rope or cable 12 when the cage or car is suspended therefrom. The automatic operating device 6 is designed, in the event of 90 the breakage of the cable, to throw the inner arms of the transverse levers 4 downwardly, and thereby swing the dogs into engagement with the guides in the ordinary manner, and as the particular construction of 95 the automatic operating device 6 does not constitute a feature of the present invention, and also as the present invention is applicable to various safety devices, further illustration of the operating device 6 is 100 deemed unnecessary. The cable 12 is secured at its lower end in a socket or clamp 13, which is connected with the upper end of the hollow rod of a link or yoke 14 of the ordinary construction.

105 The auxiliary operating device comprises

in its construction upper transversely disposed levers 15 pivotally mounted at their inner ends 16 on the top beam or other portion of the car or elevator and arranged in pairs and located at opposite sides of the said top beam, as clearly illustrated in Fig. 2 of the drawings. The outer ends of the upper levers are connected with the said links 3 by upper links 17, having their lower ends pierced by the pivots 10 and provided at their upper ends with slots 18 for the reception of pivots 19, which are carried by the outer ends of the upper transverse levers 15. The transverse levers are connected at 15 a point intermediate of their ends to branches 20 of chains 21, converging upwardly from the levers and secured at their upper terminals to the rope or cable 12 in spaced relation with the clamp. The upper 20 ends of the chains 21 are linked into openings 22 of flanges 23 of a sleeve 24, and in event of the parting of the cable from the clamp or socket 18, the chains 21 will be pulled upon and will swing the upper levers 25 upwardly with respect to the car or cage and positively carry the dogs 2 into engagement with the guides. The action of the attachment may supplement the action of the operating device 6, or be independent 30 thereof, as the dogs will be carried into engagement with the guides whether the device 6 operates or not. Also, the flexible connections between the outer levers and the cable permit an independent action of the 35 dogs, so that one dog may engage the adjacent guide in advance of the other dogs, and it will not interfere with the operation thereof, as all of the dogs will be engaged with the guides by the flexible connections 40 between the upper levers and the cable. This is an advantage, especially when the elevator car or cage is not in plumb, as with the ordinary safety device the engagement of one dog with a guide in advance of the 45 remaining dogs frequently prevents the gripping action of the remaining dogs and thereby renders the safety device inoperative and ineffectual in arresting the descent of the cage or car.

50 Any other suitable flexible connection may be employed instead of the chains, and the latter may be connected with the cable in any suitable manner.

55 In the accompanying drawings, the sleeve 24 is constructed of sections, having bolted flanges 25, but it may be of any preferred construction. Also, while the improvement is illustrated in the accompanying drawings in the nature of an attachment for a safety device, and is designed principally for such use, it may constitute the sole means for operating the dogs.

What is claimed is:

65 1. The combination with an elevator car, a cable connected therewith, and an auto-

matic safety device including a clutch and automatic mechanism for moving the clutch to its engaging position, said automatic mechanism being normally held by the cable and adapted to be released by the parting 70 of the same, of separate means including a lever arranged at the top of the car above the automatic mechanism and connected with the clutch, and a chain connecting the lever with the said cable, whereby the lever 75 will be directly actuated in the event of the parting of the cable to positively move the clutch to its engaging position.

2. The combination with an elevator car, a cable connected therewith, and an automatic safety device comprising clutches located at opposite sides of the car, and automatic mechanism for moving the clutches to their engaging position, said mechanism being normally held by the cable and adapted to be 80 released by the parting of the same, of separate clutch actuating means including levers mounted on the car at opposite sides thereof and connected with the clutches, and chains connected to the cable beyond the car 85 and extending downwardly and outwardly and also connected at their lower ends to the said levers.

3. The combination with an elevator car and a cable, of a safety device mounted on the car and including dogs arranged in pairs, lower transverse levers, an automatic operating device connected with the lower levers and normally held under tension by the cable, upper transverse levers mounted 100 on the car, flexible connections secured to the cable beyond the car and having branches connected to the upper levers, and means for connecting the upper and lower levers with the dogs.

4. The combination with an elevator car and a cable, of a safety device mounted on the car and including spaced dogs, lower transverse levers, an automatic operating device connected with the inner ends of the lower levers and normally maintained under tension by the cable, upper levers mounted on the car and fulcrumed at their inner ends and arranged in pairs, flexible connections secured to the cable beyond the car and having branches connected directly to the upper levers, and upper and lower links connecting the dogs with the outer ends of the said levers.

5. The combination with an elevator car, a cable connected therewith, and an automatic safety device comprising dogs arranged in pairs at opposite sides of the car, and automatic mechanism for moving the dogs to their engaging position, said mechanism being normally held by the cable and adapted to be raised by the parting of the same, of separate actuating means including levers arranged in pairs at opposite sides of the car and connected with the dogs, and 125 130

chains connected to the cable beyond the car and extending downwardly and outwardly, said chains having branches secured to the levers, whereby the chains are adapted to directly actuate the levers in the event of the parting of the cable from the car.

In testimony, that I claim the foregoing as

my own, I have hereto affixed my signature in the presence of two witnesses.

MATTHEW M. BEAM.
